United States Patent Office

Des. 227,859
Patented July 24, 1973

227,859

RAZOR HOLDER

Norman D. Poisson, Marblehead, Mass., assignor to The Gillette Company, Boston, Mass.

Filed May 17, 1971, Ser. No. 144,377

Term of patent 14 years

Int. Cl. D9—03

U.S. Cl. D9—186

FIG. 1 is a perspective front view of a razor holder showing my new design:

FIG. 2 is a perspective rear view of the razor holder shown in FIG. 1;

FIG. 3 is a side elevational view of the razor holder shown in FIG. 1;

FIG. 4 is a side sectional view taken along the line 4—4 of FIG. 1;

FIG. 5 is an end view from the head end of the razor holder as indicated by the line 5—5 of FIG. 3;

FIG. 6 is an end view from the opposite end of the razor holder as indicated by the line 6—6 of FIG. 3; and

FIG. 7 is a sectional view taken along the line 7—7 of FIG. 4.

I claim:

The ornamental design for a razor holder, as shown.
